UNITED STATES PATENT OFFICE

JOSEPH HENRY FULMER, OF NAZARETH, PENNSYLVANIA

FEEDING DEVICE

Application filed November 15, 1929. Serial No. 407,439.

This invention relates to a feeding device especially designed for use in connection with devices for artificially curing hay; such as shown in my pending application filed November 7, 1928 Serial No. 317,867.

The primary object of the invention is to provide a device of this character which will form the hay or material under treatment, into a wide ribbon like mass to insure the proper treating of the hay.

A further object of the invention is to provide a feeder of this type which will feed a predetermined amount of hay to the endless carriers of the apparatus with which the device is used, in such a way as to insure against clogging of the apparatus.

A still further object of the invention is to provide an adjustable means for regulating the thickness of the mass of material passing into the machine.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a feeding device constructed in accordance with the invention.

Figure 2 is a longitudinal sectional view through the feeding device.

Figure 3 is a plan view thereof.

Figure 4 is a sectional view taken on line 4-4 of Figure 2.

Figure 5 is a sectional view taken on line 5-5 of Figure 2.

Figure 6 is a sectional view taken on line 6-6 of Figure 2.

Figure 7 is a bottom plan view of the hopper.

Figure 8 is a plan view of the pusher or follower of the feeding device, a portion thereof being broken away.

Figure 9 is an end elevational view of the pusher or follower.

Figure 10 is a transverse sectional view therethrough.

Referring to the drawings in detail, the device includes an elongated box-like body portion indicated generally by the reference character 5, the same being provided with an opening arranged adjacent to the lower end thereof, to receive the lower end of the hopper 6 which is secured in position by means of the angle bars 7 and 8 respectively, which are bolted to the hopper and body portion.

The box-like body portion or receiver is inclined, as clearly shown by the drawings, the same being supported at its front end by means of the leg members 8, the rear end thereof being secured by means of the cooperating angle bars 9 which are bolted together as clearly shown by Figure 2.

The side walls of the box-like body portion 5 are provided with elongated openings 10 disposed on opposite sides of the body portion, which openings accommodate the ends 11 of the shaft 12 which connects with the pusher or follower 13. Connected with the ends 11 of the shaft 12, are links 14 that have pivotal connection with the crank shaft 15 at 16, the crank shaft being supported in bearings mounted on the frame 17, so that rotary movement of the shaft 15 will impart movement to the links 14 and shaft 12, to reciprocate the pusher or follower 13 and accomplish the purpose of the invention.

Rotary movement is imparted to the shaft 15, through the medium of the sprocket 18 mounted thereon, the sprocket 18 receiving motion from the shaft 19, through the medium of the chain 20 and sprocket 21 which

is mounted on the shaft 19. Mounted at one end of the shaft 19 is a substantially large sprocket 22 that receives motion from the shaft 23, through the sprocket 24 and chain 25 operating thereover, the shaft 23 receiving its motion from a source of power supply, such as the motor 26, through the belt 27 and pulley 28, which is mounted on the shaft 23. It will of course be understood 10 that the circuit control to the switch will be of the usual and well known construction, so that the operator may readily control the operation of the device.

Disposed within the box-like body portion 15 is a packer 29, which is of a length to extend across the body portion to restrict the area of the box-like body portion at a point adjacent to the rear end of the hopper 6. The packer 29 is supported by the threaded bolts 20 30 that have connection therewith, the threaded bolts passing through openings formed in the channel bars 31 that are arranged in parallel spaced relation with each other adjacent to the upper surface of the box-like receiver, there being provided nuts 32 on the threaded bolts for securing the packer in its positions of vertical adjustment.

Thus it will be seen that due to this construction the quantity of material forced 30 through the body portion may be regulated at the will of the operator, to facilitate the curing operation. The pusher or follower operates under the plate 33 which is spaced from the bottom of the box-like body portion 35 such a distance as to permit of free sliding movement of the packer or follower. As shown, one end of the body portion rests against the frame of the endless carrier 34 that forms a part of the apparatus for curing hay with which the device is used, so 40 that material discharged from the box-like body portion 5, will fall directly onto the endless carrier to be fed through the apparatus.

45 In the operation of the device, the circuit to the motor is completed, causing the sprockets and chains operating thereover, to transmit movement to the crank shaft 15, whereupon the links 14 are set into operation, causing 50 the pusher or follower 13 to reciprocate under the hopper 6 and force material which has been fed into the body portion, through the hopper. Thus it will be seen that the material is spread or formed into a substantially thin ribbon-like mass as it passes onto 55 the endless conveyor of the apparatus with which the device is used, so that the material may be thoroughly treated.

I claim:

60 In a hay feeding device, an elongated body portion, a hopper supported on the body portion and communicating with the interior thereof to feed material to the body portion, a packer comprising a vertically movable plate of a width to extend across the body

portion, said plate having upwardly and inwardly extended flanges, headed bolts extending through the flanges and through the body portion, the heads of the bolts engaging the lower sides of the flanges providing 70 supports for the packer, and a sliding pusher operating in the body portion and adapted to force material through the body portion forming the material into a ribbon-like mass.

In testimony that I claim the foregoing 75 as my own, I have hereto affixed my signature.

JOSEPH HENRY FULMER.
